Primary Examiner—Carol Rademaker(74) Attorney, Agent, or Firm—Kagan Binder, PLLC(57) CLAIM

The ornamental design for a cosmetic container, as shown and described.

DESCRIPTION

FIG. 1 is a perspective view of a cosmetic container of the present design;

FIG. 2 is a bottom plan view of the cosmetic container of FIG. 1;

FIG. 3 is a right side elevational view of the cosmetic container of FIG. 1;

FIG. 4 is a front elevational view of the cosmetic container of FIG. 1;

FIG. 5 is a left side elevational view of the cosmetic container of FIG. 1;

FIG. 6 is a top plan view of the cosmetic container of FIG. 1; and,

FIG. 7 is a rear elevational view of the cosmetic container of FIG. 1.

The broken lines shown in the drawings are for environmental purposes only and form no part of the claimed design.
